CLAIM

The ornamental design for a therapy apparatus, as shown and described.

DESCRIPTION

FIG. 1 is a front, right and top perspective view of a therapy apparatus according to a first embodiment showing our new design;

FIG. 2 is a rear, left and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, right and top perspective view of a therapy apparatus according to a second embodiment;

FIG. 10 is a rear, left and bottom perspective view of FIG. 9;

FIG. 11 is a front elevational view of FIG. 9;

FIG. 12 is a rear elevational view of FIG. 9;

FIG. 13 is a left side elevation view of FIG. 9;

FIG. 14 is a right side elevation view of FIG. 9;

FIG. 15 is a top plan view of FIG. 9;

FIG. 16 is a bottom plan view of FIG. 9;

FIG. 17 is a front, right and top perspective view of a therapy apparatus according to a third embodiment;

FIG. 18 is a rear, left and bottom perspective view of FIG. 17;

FIG. 19 is a front elevational view of FIG. 17;

FIG. 20 is a rear elevational view of FIG. 17;

(Continued)

FIG. 21 is a left side elevation view of FIG. 17;
FIG. 22 is a right side elevation view of FIG. 17;
FIG. 23 is a top plan view of FIG. 17; and,
FIG. 24 is a bottom plan view of FIG. 17.
The dash-dash broken lines in the drawings depict the
portions of the therapy apparatus which form no part of the
claimed design.
